(Cl. D87—2)

To all whom it may concern:

Be it known that we, John De Pasquale and Alexander Westerman, citizens of the United States, residing at Brooklyn, in the county of Kings, city and State of New York, have invented a new, original, and ornamental Design for a Top Band for Bag Frames, of which the following is a specification, reference being had to the accompanying drawing, forming part thereof.

In the drawing

Fig. 1 is a front elevational view of a top band for bag frames showing our new design;

Fig. 2 is a bottom plan view thereof;
Fig. 3 is a sectional view on the line 3—3 of Fig. 1; and

Fig. 4 is a sectional view on the line 4—4 of Fig. 1.

We claim:

The ornamental design for a top band for bag frames, substantially as shown.

JOHN DE PASQUALE.
ALEXANDER WESTERMAN.
